(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with animated graphical user interface showing the claimed design;

FIG. 2 is a second image thereof;

FIG. 3 is a third image thereof;

FIG. 4 is a front view of a second embodiment of a display screen or portion thereof with animated graphical user interface showing the claimed design;

FIG. 5 is a second image thereof; and,

FIG. 6 is a third image thereof.

The outermost dashed broken lines in FIGS. 1-6 show a display screen or portion thereof, and form no part of the claimed design. The other dashed broken lines in FIGS. 1-6 show portions of the animated graphical user interface that form no part of the claimed design.

The dot dash broken lines in FIGS. 3 and 6 and the grayed out areas within the dot-dash broken lines show portions of the animated graphical user interface that form no part of the claimed design.

The subject matter in this patent includes a process or period in which an image changes into another image. The process or period forms no part of the claimed design.
